UNITED STATES PATENT OFFICE.

ELVERTON I. HOWARD, OF WESTFIELD, NEW YORK; ELSIE R. HOWARD EXECUTRIX OF SAID ELVERTON I. HOWARD, DECEASED; ALEXANDER THOMPSON EXECUTOR OF SAID ELSIE R. HOWARD, DECEASED; SAID ALEXANDER THOMPSON, EXECUTOR, ASSIGNOR TO PRIMOLITE COMPANY, OF INDIANAPOLIS, INDIANA.

LENS-HOLDER FOR HEADLIGHTS.

1,344,694.

Specification of Letters Patent. Patented June 29, 1920.

Application filed July 25, 1919. Serial No. 313,254.

To all whom it may concern:

Be it known that I, ELVERTON I. HOWARD, a citizen of the United States, residing at Westfield, in the county of Chautauqua 5 and State of New York, have invented certain new and useful Improvements in Lens-Holders for Headlights, of which the following, taken in connection with the accompanying drawings, is a specification.

10 The invention relates to improvements in headlights for vehicles; and the improvement consists in providing means for holding the lens from turning. Some of the best improved light controlling lenses are 15 of the refracting type wherein the glass is cast in prismatic forms so as to throw the light downward or diffuse the same so as to protect the eyes of the passerby or bystander. In order that said prisms or other 20 formations of the glass shall have the desired effect, the glass lens must be held in one position so that it cannot rotate or turn sidewise and thereby throw the light to one side or the other according as the lens is 25 turned. In order to prevent such movement or turning, the outer edge portion of the lens is provided with an opening, preferably dovetail shaped, into which a resilient holding means is inserted preferably extending 30 beyond the surface of the lens at each side thereof so that a plurality of these resilient holding points under pressure between the lamp rim and the packing for the lens hold said lens firmly in position in such a resili- 35 ent manner that the lens is safely retained and at the same time cannot turn or work loose by the continual jogging in driving the car over rough roads; and the invention consists in the novel features and combinations 40 hereinafter set forth and claimed.

In the drawings, Figure 1 is an elevation of the front of the headlight with a refracting lens held at a plurality of points, preferably three, the rim portion being broken 45 away to show the preferred form of holding means. Fig. 2 is a sectional view through said holding point showing the rim and a portion of the lens of the reflector and the resilient holding means for said 50 lamp. Fig. 3 is an elevation of the top portion of the lens showing the dovetail shaped opening in the edge portion thereof with the dovetail shaped block at one side

of said top portion of the lens ready to be inserted. Fig. 4 is a sectional view of said 55 edge or rim portion of the lens alongside the resilient block showing the compressible nature of said block and the manner in which it bulges beyond the front and rear faces of the lens rim to be compressed between the retaining rim of the headlight and the packing for said lens. Fig. 5 is a similar view of a top portion of the lens showing a modification consisting of a round hole and a round block for compressing 60 into said hole. Fig. 6 is a similar view of a top portion of the lens showing a modification consisting of a round hole and a round block for compressing 65 into said hole.

Like characters of reference refer to corresponding parts in the several views.

The numeral 10 designates the lens which is preferably cast in glass with the prismatic 70 or other diffusing means or formations therein, and an edge or rim 11 extending around the same.

An opening 12 is provided in the rim 11 which is preferably dovetail shaped to receive therein the dovetail shaped resilient block 13. The block 13 is preferably made of rubber and larger than the opening 12 so as to be compressed into the same and bulge beyond each side, not only that it may not 80 slip from the opening 11, but also that it may be compressed between the metal rim 14 of the headlight and the packing 15 against which the rim 11 of the lens 10 is held by the metal rim 14. 85

The blocks 13 are provided at a plurality of points in the rim 11, preferably three at equidistant portions of the lens 10, so that when under heavy compression by the rim 14, the resilient or rubber blocks 13 will 90 resiliently hold the lens 10 firmly in position by their strong frictional contact, and at the same time absolutely prevent said lens 10 from turning in either direction. The lens 10 is mounted by simply placing 95 the top block 13 at the exact center of the rim of the casing 16, the lens 10 will thus be mounted correctly in position so that the crosswise prisms or other diffusing means will refract the light on the roadway as de- 100 signed.

The modification shown in Fig. 5 is merely a different shaped or round opening 17 and a round resilient plug 18 which is compressible within the hole 17 and performs 105 substantially the same office as the dovetail

shaped block 13. The dovetail shaped block 13 is preferred because it has a longer grip upon the packing 15 and removable rim 14 and is also not so easily dislodged. It is apparent that in the round opening 17 a coil spring might be used and serve a good purpose in holding the lens 10 against turning. The resilient rubber plug is preferred because of its resilient nature and added 10 frictional holding qualities.

I claim is new:

1. In combination with a vehicle or like lamp, a lens therefor covering the front of the lamp and having a plurality of dove-tail shaped openings in the edge thereof, and resilient dove-tail shaped blocks fitted in and filling said openings and of a thickness to extend outwardly beyond the front and rear faces of the lens and beyond the

peripheral edge of the lens when under compression. 20

2. In combination with a vehicle or like lamp, a lens therefor covering the front of the lamp and having a plurality of openings in the edge thereof and resilient blocks 25 fitted in and filling said openings and of a size to extend outwardly beyond the front and rear faces of the lens and to have their peripheral edge portions disposed beyond the peripheral edge of the lens when under 30 compression.

In testimony whereof I have affixed my signature in the presence of two witnesses.

ELVERTON I. HOWARD.
